H. HART.
WASHING MACHINE.
APPLICATION FILED DEC. 1, 1916.

1,287,302.

Patented Dec. 10, 1918.

Inventor,
Kiram Kart.

UNITED STATES PATENT OFFICE.

HIRAM HART, OF ST. LOUIS, MISSOURI.

WASHING-MACHINE.

1,287,302.

Specification of Letters Patent. Patented Dec. 10, 1918.

Application filed December 1, 1916. Serial No. 134,342.

To all whom it may concern:

Be it known that I, HIRAM HART, a citizen of the United States, residing at St. Louis, in the State of Missouri, have invented new and useful Improvements in Washing-Machines, of which the following is a specification.

My invention relates to improvements in washing machines and the object of my improvements is to construct a machine of the funnel-plunger type, in which each funnel has a tubular staff carrying a check valve whereby to close the plunger against the escape of air during a downward or working stroke, and to open the plunger to atmosphere, on the upward stroke to admit air to free the clothes from the plunger and to increase the circulation of the water through the clothes.

A further object of the invention is to construct an inexpensive, durable, efficient and easily operated machine, which is adaptable for use with any ordinary tub, without employing fastening devices for the tub and to which none of the machine elements are attached, so that a number of tubs may be successively used without changes to the machine.

With the foregoing and other objects in view, which will be made clear hereinafter, my invention consists in the novel arrangement and construction of parts, which will be hereinafter fully, clearly and concisely set forth in my specification, pointed out in my claim and illustrated by the accompanying drawing in which the figure is an elevation of a machine embodying my invention, with certain parts broken away and in section, to illustrate certain normally concealed details of structure.

Referring by numerals to the drawing 1, designates the base of the machine, which is provided at its one end with a hinged leaf 2, for the support of a clothes wringer 3, and a releasable brace 4, for securing the leaf at an angle relative to the base, and whereby the leaf may be lowered at times to remove the tub from the base.

Centrally from the base there arises a pivot 5, which supports and holds concentrically with the base, a table 6, which is further supported over the base by a plurality of casters 7, and upon which table there is placed a tub or other vessel in which the water and clothing are contained.

Arising from the base at a point opposite

the wringer is a standard 8, provided within its length with a substantially right angled bend 9, serving as a guide for a driven shaft 10, which carries at its lowermost extremity a cross pin 11, and surrounding the shaft and the said cross pin is a sleeve 12, whose interior is non-circular, whereby the sleeve is caused to rotate with the shaft, but which will permit free relative lengthwise movements. Carried by the sleeve is a short shaft 13, mounted for rotation in ears 14, outstanding from the standard 8, and secured to said short shaft is a spur gear wheel 15, arranged to mesh with circular rack 16. 60 70 secured to said table.

Mounted on the standard 8 above the bend 9 and vertically secured, adjustably, thereto by means of the screws 17 is a head casting 18 having bearings 19 for a driving shaft 20 having a crank 21 connected therewith.

The shaft 20 is connected with the driven shaft 10 by means of a bevel gear 22 and when the crank is manipulated the table 80 and tub carried thereby will be rotated.

Extending at right angles to the supporting stem of the head casting is a pair of guides 23 through which the tubular staffs 24 are extended for vertical reciprocation. 85 Arranged between the guides 23 are the rods 25 between which the cross heads 26 are mounted for reciprocation, said cross heads being adjustably secured to said staffs 24, whereby the full stroke may be imparted 90 to the staffs 24, said staffs being held in different altitudinal locations in order to adapt the machine to different bulks of matter to be washed. Mounted in the head casting over the guides 23 is a bearing in which is 95 supported a bevel gear 27 which meshes with a bevel gear 28, secured to the driving shaft. Rotatably mounted with the gear 27, is a pair of cranks 29, each of which connects with a cross head 26 by means of a link or pitman 30.

The crank 21 is removably secured to the driving shaft, so that in the event that other power is available the machine may be so driven, and for this purpose I provide a 100 wheel 31 which may be employed as a belt wheel for power or as a fly wheel for use with the crank.

Each of the tubular staffs carries, at its upper end, a check valve 32 of any desired 110 or ordinary construction arranged to automatically act to admit air to the staff on

the upstroke and to check or prevent the escape of air on the down stroke.

The numeral 33 designates funnels having tubular extensions 34 which are slipped over the lower ends of the staffs, the staffs having pins 35 therethrough to limit the movement of the funnels in the one direction. The tubular extensions are each provided with a flange 36, which forms an abutment for the extensile spring 37, the opposing abutment being collar 38 adjustably secured to the staff, so as to provide adjustment for the springs. To prevent leakage of air between the funnel extensions and the staffs, I place packing 39 within the extension surrounding the staff.

The operation of the machine is as follows:—

Having the machine set up and assuming that there is water and clothes in the tub I turn the crank, rotating shaft 20 and the set of bevel gears 22 and also the bevel gear 28. The rotation of gears 22 rotates shaft 10 and sleeve 12 by means of pin 11. Sleeve 12 rotates shaft 13, which in turn operates gear 15. Gear 15 operates gear 16 with which it is in mesh and this latter gear operates the table about pivot 5 and thereby revolves the tub or other vessel carried by table 6. Concomitantly therewith gear 28 which is also revolving operates gear 27 and the pair of cranks 29, which in turn actuate the links 30 and reciprocate the crossheads 26. Crossheads raise and lower the staffs 24, carrying with them the funnel plungers 33. In the event of a thick layer of clothing being disposed under the funnels so that they are restricted in their course of travel staffs 24 continue to descend and depress the collars 38 compressing the springs 37. As the plunger 33 strikes the clothing it compresses it and expels the water which displaces the air contained in the funnel. This air is

forced through the clothing aiding the water circulation and thus enabling free circulation of the wash water. Upon the return stroke of the funnel the check 32 opens, admitting a new supply of air to be used in the next operation of the funnel. When the clothing has been sufficiently washed the head 18 is raised, being released by screws 17, until the funnels reach a level above the top of the tub. As soon as the funnels have been removed from the tub either the clothing may be bodily removed, or they may be fed to the wringer, or the water may be removed and a fresh supply added for rinsing or the tub and contents may be totally removed from the platform.

Having thus described my invention what I claim as new therein and desire to secure by Letters-Patent therefor is—

In combination with a rotatable tub-support a vertical reciprocable clothes pounding device and a base upon which the tub support may rotate, a unit comprising a standard, integral means for securing the standard to the base and integral relatively spaced ears, a second unit comprising an element for securing to said standard, bearings for a driving shaft and bearings for a gear for moving the clothes pounding device, means providing relative vertical adjustment of said units, and a gear, partially supported by said ears for rotating the tub-support upon a rotation of the driving shaft and means connected with said last mentioned gear for allowing adjustment of said units.

In testimony whereof I have signed my name in the presence of two subscribing witnesses.

HIRAM HART.
